FOLDING WALL TABLE

James Roland Boggs, Atlanta, Ga.

Application July 26, 1950, Serial No. 11,420

Term of patent 7 years

(Cl. D33—14)

To all whom it may concern:

Be it known that I, James Roland Boggs, a citizen of the United States, residing at Atlanta, in the county of Fulton and State of Georgia, have invented a new, original, and ornamental Design for a Folding Wall Table, of which the following is a specification, reference being had to the accompanying drawing, forming part thereof, and wherein:

Fig. 1 is a perspective view of a folding wall table, in folded position, showing my new design.

Fig. 2 is a side view of the folding wall table shown in Fig. 1.

Fig. 3 is a front view of the table shown in Fig. 1 in extended position.

Fig. 4 is a side view of the table as shown in Fig. 3.

I claim:

The ornamental design for a folding wall table, substantially as shown.

JAMES ROLAND BOGGS.
